UNITED STATES PATENT OFFICE.

HENRY C. WATERS, OF BOSTON, MASSACHUSETTS.

POSTING DEVICE.

1,187,685.

Specification of Letters Patent. Patented June 20, 1916.

Application filed May 1, 1914. Serial No. 835,743.

To all whom it may concern:

Be it known that I, HENRY C. WATERS, a citizen of the United States, residing at Boston, in the county of Suffolk and State of Massachusetts, have invented new and useful Improvements in Posting Devices, of which the following is a specification.

This invention relates to improvements in posting devices.

10 More particularly it relates to devices for handling records, as for example, records of cash receipts, so that they can be posted in the book or account where they belong with a maximum of ease and convenience, and 15 with a saving of time over that hitherto required.

The invention is illustrated as it may be applied for posting the items of daily cash receipts. In a business where numerous 20 items of this sort occur it is desirable to record them as they are received. For convenience the accounts to which they must ultimately be posted are always arranged in alphabetical order, or in geographical or 25 numerical order or according to some other system, and in a business of magnitude they occupy a number of different books or drawers; but the cash receipts occur 30 miscuously. Consequently, when the receipts have been recorded in the order of 35 their arrival the posting involves not a little confusion, walking back and forth; and searching, to find the next account after posting each item. This consumes time which has a money value, and involves other 40 undesirable arrangements or conditions.

The objects of the present invention are 45 accomplished by providing a sheet upon which items may be entered as they are received, and means for making a copy of each entry in such a form that it can easily be handled separately from the copy of every other entry. All of the copies are then sorted into alphabetical or whatever other order conforms to the arrangement of the 50 accounts to which the items are to be posted. Specifically, this is accomplished by providing in connection with the sheet of original entry a series of cardboard sheets, which may 55 conveniently be five in number, each of substantially the same size as the sheet of original entry, and a sheet of carbon copying paper; and then making the original entries in such locations that each successive entry is spaced at a certain distance from the last preceding one according to a regular sys-

tem, as by skipping five lines on the sheet. After the original entry sheet has once been covered in this manner, the cardboard containing the copies of the entries may be removed; and the next entries may then be made at like intervals on the sheet of original entry using some of the lines that were previously skipped, and getting the carbon copies of those entries on the second sheet of cardboard; and so the process may go on until all of the spaces in the sheet of original entry have been filled, and the copies of those entries have been at the same time distributed over the five cardboards at intervals. The cardboard sheets may be then cut into sections or cards bearing one entry each. Owing to the intervals these cards will be of convenient size for handling, and may be quickly arranged in the same order as the 75 accounts. The posting can then be done from the copies, and can proceed smoothly and rapidly and with minimum consumption of time.

The patent is not limited to the particular embodiment illustrated; and it is intended to cover by the claims whatever features of patentable novelty exist in the invention disclosed.

In the accompanying drawings:—Figure 80 1 is a plan illustrating one embodiment of the invention, or means for practising it; Fig. 2, an edge elevation of the same; Fig. 3 is an elevation of the opposite edge of the 85 same; Figs. 4 and 5 are plans of cards produced during practice of the invention; Fig. 6 shows in perspective a detail that may be used in a modified form of applying the invention; and Fig. 7 shows a card produced 90 thereby.

Referring to the drawings, 10 represents 95 a sheet of original entry; 9 is a carbon copying sheet; and 11, 12, 13, 14 and 15 are sheets of cardboard or stiff paper arranged 100 in a stack underneath. Suitable means may be provided for holding a part or all of them in place, and for making clear copies that register properly with the original, one form of means being illustrated in Figs. 1, 2 and 3, so that when anything is written 105 on sheet 10 the carbon sheet will produce a duplicate mark on the cardboard which is next beneath it. The sheet of original entry is provided with any suitable ruling, or may be entirely blank. As herein illustrated it 110 has the usual horizontal lines for entries of items, and vertical ruling for dollars and

cents, with spaces at the top for date, number, etc. Holes 16 are represented, to indicate that it may be a leaf of a book.

The numeral 50 represents a board or platen adapted to support the sheets so that a clear copy is made by the carbon copying sheet on the upmost cardboard sheet of whatever is written on the original entry sheet. Any suitable means may be employed to hold the sheets in proper place and to carry out the essentials of the invention in other respects. The means shown is adapted to use for hand written entries, and has a spring clamp 51 adapted to press the top portion of the original entry and the carbon sheets firmly upon the platen. The platen carries guides or abutments 52 at the top, 53 at the side, and 54 at the bottom, so that the entire collection of sheets can be stacked against the corner 53, 54, and made to register uniformly together. The cardboard sheets need not be either as wide or as high as the original entry sheet, but need underlie only the lines on which entries are made; and preferably they do not, in the type of apparatus illustrated, reach to the clamp 51. In use it is then only necessary to remove the topmost cardboard sheet after each going over of the original entry sheet as now to be described.

At the side of the platen is a scale marking positions of successive lines on the original entry sheet, and at suitable intervals, which intervals as here illustrated, are at every fifth line, the mark of the scale is heavier thus distinguishing certain lines from the others. These lines are for convenience called "key-lines" herein, and are marked O in the drawing. They indicate the positions at which entries may be made in a plurality of series covering the sheet. The entries of the first series may be made on the lines next below the key-lines, for example, on the lines marked a. This will produce copies on the cardboard sheet 11 with intervals between them as between a and a in Fig. 4. The original entry sheet having been thus covered at intervals, the cardboard sheet 11 containing the copies of its entries will then be removed, and the next entries will be made at similar intervals, using the lines second below the key-lines and marked b, the copies of these entries being made on the second cardboard sheet, 12. The next entries will be made on the lines third below the key-lines O, viz., the lines c, and their carbon copies on the third cardboard sheet, 13, the sheet 12 having been removed. Similarly original entries are made on the lines d, with simultaneous copies spaced at intervals on the cardboard 14; and then all the remaining lines on the sheet of original entry, being the lines e, are filled and their copies obtained on the cardboard sheet 15. The result is that all

of the original entries are contained on the sales cash sheet in the usual compact form in close proximity to each other, and also are distributed by copies, over five cardboard sheets, with blank spaces or intervals between them. These cardboard sheets may then be cut by any suitable mechanism into uniform sections or cards, each having a width equal to five lines of the original entry sheets, as illustrated in Figs. 4 and 5. The apparatus should be designed so that the cards thus formed are of suitable size, edge and stiffness for convenient and quick handling. After they have been distributed or re-arranged into alphabetical order, or into whatever order is most convenient, according to the system on which the accounts are arranged in the ledgers, each bookkeeper can take the cards that pertain to accounts in a particular ledger, and can proceed regularly through the stack of cards and through the book, posting the items from the cards. Meanwhile, the handling of the cash itself has not been delayed, and it has been possible for the making of entries to proceed as fast as the cash has come in.

It will be understood that the clipping of sheets into cards is most conveniently performed by some sort of cardboard clipping machine in which there is a gage for determining a uniform length to be cut at each stroke. As the sheets illustrated are designed, their top edges register with the first key-line, O, of the original entry sheet. Consequently, the clipper gage may be set at a five-line measure, and then it will, at each stroke, sever the cardboard on a line that was under one of the key-lines, severing section 11' or 12', etc., with a single item on it. So far as the invention has yet been herein described, such item will be either at the top of the card thus cut, or at some distance below its top, depending upon how far its original entry is below the key-line O next above it. Figs. 1 and 2, however, show a means which may be employed, if desired, to bring it about that the names shall be in the center of the cards thus cut, however their original entries be related to the key-lines. A series of laterally extending holes marked 61, 62, 63, 64, 65, are represented as being made in the lateral abutment 53, and a pin 60 is represented as adapted to fit into any one of these holes to project for a distance into the space under the original entry sheet, 10. This constitutes an adjustable abutment against which the upper edge of the cardboard sheet may be pushed in order to fix its position. The hole 61 is so located that when the cardboard is thus positioned against the pin 60, projecting from hole 61, the line a on which the first entry is to be written will be below it at a distance equal to half the interval between key-lines. Con-

sequently, when this cardboard sheet is clipped into cards, all of the entries made upon it, being copies from lines of the first series, *a*, will be midway of their cards at 5 the position indicated in Fig. 7. The second hole 62 is at a distance below the first hole 61 equal to the width of one of the lines for writing an original entry. Consequently, if this be used as an abutment for the top of 10 the second cardboard sheet, the entries made on lines *b* will be reproduced at the same distances below the top of the cardboard as were the entries written on the series of lines *a*. The same principle governs the fixing 15 of the other holes 63, 64 and 65; and all cards will have their items centrally located. In using this feature of the invention, only one of the set of cardboards is in place at a time. When it has been filled the person 20 using the apparatus takes it out, shifts the pin 60 to the next lower hole, and puts the next cardboard against the pin in its new position. It is not necessary in either case to move the original entry sheet 10, which 25 may remain held by the clamp 51, the lower part of the sheet being lifted to take out the filled copy sheet, and to put in a fresh one if the modification just described be in use. It is found very convenient to use the first 30 described method, placing a stack of five copy sheets under the original entry sheet at the beginning and then removing one when each series has been completed. The corner guides 53, 54, enable the cardboards 35 to be kept stacked in proper position. The location of the item on the card, after it has been clipped, will show to which series the card belongs; and if it be desired to have a further means for easily discovering the location 40 of the original entry, that may be provided by numbering in advance the different strata of each cardboard sheet, which ultimately will be severed from each other, as illustrated in Figs. 4 and 5, where the 45 numbers 9 and 10 on the cards combined with the position of the items at the level indicated by the reference numerals *a* show that the two cards of Fig. 4 were the lowest two cards from the first copy sheet, because 50 it is known that there are ten such cards per copy sheet, of which these are numbers 9 and 10, and that those in Fig. 5 were the lowest two cards from the second copy sheet, an inference drawn by the same process of 55 reasoning. Any further identification desired is easily obtainable by running a rubber-stamp dating wheel over the original entry sheet and over each cardboard sheet pertaining to it. 60 While the invention has been described as it may be embodied in apparatus for facilitating a particular bookkeeping operation, it will be found that the invention is applicable to other bookkeeping operations 65 and to many other kinds of records and

similar uses. It is applicable for use in connection with any business system where it is desired to make entries in close proximity to each other on a sheet, and to distribute those entries to different destinations. 70

The means for indicating the locations for items, in order to provide regular intervals in which items in other series may later be entered, may take various forms. The form illustrated in Fig. 1 consists of marking a 75 scale beside the sheet, with distinctive marks for the key-lines. The indicating means might, however, consist of distinctive marks printed at regular intervals on the paper itself; or any other suitable means might be 80 employed to indicate the lines, or to aid in selecting the location at which the entries should be made in order to have the entries of each series placed at regular intervals sufficient to contain the similarly spaced entries of the other series. 85

I claim as my invention:

1. A device for handling entries comprising a platen, a clamp adapted to hold an original entry sheet thereon; means indicating positions on the original entry sheet for a plurality of series of entries, the individual entries in each such series being spaced apart and the several series overlying each other, each with its entries occupying the spaces of the other series; means for positioning successive copy sheets in determinate registry with the original entry sheet; and a plurality of copy sheets, one for each series having its record space of substantially the same 95 size as the record space of the original entry sheet, adapted to underlie the original entry sheet removably and to engage said positioning means, but not said holding means; said copy sheets being severable into sections 100 for separate handling. 105

2. A device for handling entries comprising a platen; abutments for positioning an original entry sheet and successive copy sheets in registry together thereon, means 110 indicating positions on the original entry sheets for a plurality of series of entries, the individual entries in each such series being spaced apart, and the several series overlying each other, with entries pertaining to each series occupying spaces of other series; and a plurality of copy sheets, one for each series, severable into sections for separate handling, each such section having the width of a single-entry copy plus one of said 115 spaces between individual entries in a series. 120

3. A device for handling entries, comprising the combination, with an original entry sheet of means for spacing entries thereon in a plurality of series, the entries in each series being separated from each other by intervals in which are entries in other series; and a plurality of copy sheets, on each of which is reproduced one of said series, said 125 copy sheets being severable into sections 130

4 containing each a single entry-copy, for handling.

5 4. A device for handling entries, comprising the combination, with an original entry sheet, of distinctive marks arranged in a uniform scale, indicating positions spaced apart for entries on the sheet in a plurality of series, the intervals between the entries in each series containing entries in other 10 series of said plurality; and a plurality of copy sheets, one for each series, severable for handling into sections, each containing the copy of a single entry, and having substantially the width of one entry plus one 15 interval.

5 5. The art of making, assembling, and at the same time separating memoranda, comprising the entering of a portion of the items on an assembly sheet at determinate 20 intervals apart extending over the sheet,

and simultaneously making copies thereof on a copy sheet; removing the copy sheet; entering additional items in said intervals on the assembly sheet, at similar determinate intervals extending over the assembly 25 sheet and including the first made entries; and making copies thereof simultaneously on another copy sheet; the original intervals on the assembly sheet being by this method filled with items, while the copies of such items are individually separated by spaces; and severing the copy sheets into sections each containing the copy of one item; for handling.

Signed by me at Boston, Mass., this 35 fourth day of April, 1914.
